UNITED STATES PATENT OFFICE.

OSCAR KERSTEN, OF BERLIN, GERMANY.

CARBURETER.

1,199,189.

Specification of Letters Patent. Patented Sept. 26, 1916.

Application filed December 3, 1913. Serial No. 804,478.

To all whom it may concern:

Be it known that I, OSCAR KERSTEN, a subject of the German Emperor, residing at Turmstrasse 48, Berlin, N. W., in the German Empire, have invented certain new and useful Improvements in Carbureters, of which the following is a specification.

This invention relates to spray carbureters of the type in which additional air is introduced into the mixture before passing out through the throttle, the admission of said additional air being regulated by the rotation of one cylindrical member in relation to the other so that similar ports in each register more or less according to the requirements of the engine; and has for its object to provide improved means whereby such additional air can be conveyed to the mixture, before it reaches the throttle, in the form of vortices and therefore in a finely divided state.

My invention consists in constructing a carbureter as hereinafter described and as particularly pointed out in the appended claims.

I will now describe my invention with reference to the accompanying drawing which illustrates an embodiment of my invention.

In the upper portion *a* of the carbureter, the throttle valve *d* is mounted on the spindle *f* and secured thereto by means of the screw *g*. It is controlled by the lever *e*. The upper portion which is formed as a preliminary heater, is secured on the lower portion *b* by means of four screws *q*. The lower portion is formed as a fuel reservoir in which the float *h* is provided. Fuel is supplied to the reservoir through the conduit *p, n, s*. The supply is controlled by the needle which is raised or lowered by the lever *t* pivoting about the point *v*. From the fuel reservoir a conduit leads to the fuel nozzle *i* the cross-section of the outlet of which is adjustable as desired by the screw *k*. The fuel leaves the reservoir, enters the nozzle and is carried away by the drawn-in air. Between the upper portion *a* and the lower portion *b* the middle portion *c* is provided, which carries the controller *y* of the

additional air supply. The latter consists of a plurality (for instance 3) of concentric rings formed with apertures, and which are relatively staggered. The air therefore does not reach directly the fuel-air mixture but strikes the various rings and becomes finely divided. The additional air is supplied under all conditions in such quantities that the fuel-air mixture is always approximately of the same composition. The rings may be mounted at different distances apart (for instance, 1, 2, or 3 mm.). The resistance offered by the rings, produces a uniform admission of air and a more intimate mixture with the mixture coming from the sprayer.

The main advantage of the present arrangement resides in the fact that movable parts such as balls, valves or the like are avoided, which could easily give rise to un-uniform operation of the engine.

Upon the outermost ring of the additional air controller a rotary valve *y'* is mounted; being formed with the same number of apertures as the ring inclosed by it. By displacing the valve, the apertures formed at the outer edge of the additional air controlled, are partly covered and the current of air is thus controlled. The displacement of the ring can be effected from the exterior by means of the arm *y'*.

What I claim and desire to secure by Letters Patent of the United States is:—

1. In a carbureter comprising an upper portion containing the throttle valve, an intermediate portion for supplying secondary air to the mixture before it passes to the throttle and a lower portion containing a fuel reservoir and centrally thereof a primary air inlet and a fuel nozzle, means for supplying a quantity of finely divided secondary air comprising a plurality of concentric rings, said rings being spaced apart, and each ring being formed with openings, which are relatively staggered.

2. In a carbureter comprising an upper portion containing the throttle valve, an intermediate portion for supplying secondary air to the mixture before it passes to the throttle and a lower portion containing a

fuel reservoir and centrally thereof a primary air inlet and a fuel nozzle, means for supplying a quantity of finely divided secondary air comprising a plurality of stationary concentric rings having openings which are relatively staggered, said rings being arranged at different distances apart, a perforated cylindrical valve surrounding

the outermost ring, and means for rotating said valve.

In testimony whereof I affix my signature in presence of two witnesses.

OSCAR KERSTEN.
